UNITED STATES PATENT OFFICE

CHARLES E. MILLER, OF PITTSBURGH, PENNSYLVANIA

INSULATOR

Application filed April 9, 1929. Serial No. 353,782.

This invention relates to insulators and more particularly to the type known as wire holders in which a hole extends transversely through the body portion to receive an associated electric wire directly, or to receive a tie wire employed to tie the electric wire to the insulator.

Insulators of this type are usually provided with a supporting pin extending outwardly from the base and, as heretofore constructed, these supporting pins have generally been secured to a metal plate extending across the bottom of and secured to the porcelain so as to form a metallic base for the entire structure. The presence of this metal is objectionable due to corrosion and rusting and the resultant weakening of the structure and the discoloration of the associated wall or other support. Those insulators in which the metallic base has been eliminated have consisted merely of a supporting pin cemented in a pin receiving hole in the bottom of the porcelain. Such an arrangement not only provides a comparatively weak construction, but allows the associated electric wire to drop if the porcelain is broken or fractured.

An object of this invention is to provide an insulator of the type set forth constructed and arranged to overcome the above set forth objections.

A further object is to provide a wire holder constructed and arranged to prevent dropping of the associated wire in case the porcelain body breaks.

A still further object is to provide a wire holder of simple, rugged construction which will be cheap and easy to manufacture and assemble.

These and other objects which will be apparent to those skilled in this particular art are attained by means of the invention illustrated in the accompanying drawings in which Fig. 1 is a perspective view of a wire holder constructed in accordance with one embodiment of this invention. Fig. 2 is a transverse sectional view thereof, and Fig. 3 is a similar view on the line 3-3 of Fig. 2. Fig. 4 is a view similar to Fig. 2, showing a different way in which the supporting pin

can be connected to the insulator body portion.

The particular embodiment of this invention which has been chosen for the purposes of illustration is shown in connection with the body portion 10 of a wire holder formed of porcelain, glass or other suitable insulating material and having the usual groove 11 in the end thereof and a wire hole 12 extending transversely through the body portion. 55 An insulator supporting pin 13 extends into a pin receiving hole 14 in the base of the body and suitable means is provided for positively locking the pin in position without either cementing the pin in the receiving hole 60 or providing a metal base to the body portion 10. 65

As illustrated in Figs. 1 to 3, the body portion 10 is provided with grooves 15 extending longitudinally along the outer surface 70 thereof and formed on diametrically opposite sides. At one end, the grooves terminate in a passage 16 extending transversely through the body portion from one groove to the other and intersecting the inner end of 75 the pin receiving recess 14. In the form illustrated in Figs. 1 to 3, a more or less ductile metallic locking member 17 is inserted through the passageway 16 and the ends 80 thereof are bent so as to lie within the grooves 15. A suitable joint is formed between the pin 13 and that portion of the locking member 17 which intersects the pin receiving passage 14 for locking the pin in place. The pin head 18 is of a size capable of passing 85 through the wide portion 19 of a slot formed in the locking member 17, but too large to pass through the narrow portion 20 of such slot. The head is provided with undercut 90 grooves for receiving the edges of the narrow portion of the slot after the head has passed through the wide portion thereof and been moved into the narrow portion. As a result of this construction, when the locking member is positioned with the wide portion of the slot in the pin receiving recess 14, the pin can 95 be inserted in place and the head 18 thereof passed through the slot. Longitudinal movement of the locking member 17 through 100 the passage 16 so as to bring the narrow por-

tion 20 of the locking slot beneath the pin head 18 effectively locks the pin in position and the locking member is positively secured in place by the bent ends thereof which lie in the longitudinally extending grooves 15. A rivet or other form of fastening pin 22 extends through a passage 23 in the body 10 which connects the outer ends of the grooves 15 and is located on the opposite side of the 10 wire receiving hole 12 from the passage 16.

It will be apparent that the present invention provides a wire holder having a plain porcelain base and in which the supporting pin is positively and mechanically locked in 15 place and which at the same time is of such construction and arrangement that breaking of the porcelain body portion 10 will not permit the associated wire to drop for the reason that either such wire or a connected tie 20 wire, extending through the wire opening 12, will be held against dropping by the surrounding loop formed by the locking member 17 and the rivet or tie rod 22.

In Fig. 4 the pin 13 is provided with a head 25 18 and similar in all respects to the pin illustrated in Figs. 1 to 3. The locking member 34 is similar to the locking member 17, the only difference in the construction being that instead of the passages 16 extending through 30 the body of the insulator itself, a groove 35 is formed in the base of the insulator, the groove being of sufficient depth to more than receive the locking member 34 so that the latter is well below the surface of the insulator bottom 36. The connection between 35 the pin head 18 and the locking member 34 is similar to that shown in Figs. 2 and 3.

It will be apparent that an almost unlimited number of ways of securing the supporting 40 pin 13 in place is possible and although I have described certain specific ways of doing so and illustrated certain specific forms of construction, it will be understood that various changes, additions, omissions and 45 substitutions can be made therein without departing from the spirit of this invention or the scope of the appended claims.

What I claim as new and desire to secure by Letters Patent is:

50 1. An insulator having in combination a body provided with a hole extending transversely therethrough for connection to an associated wire or the like and channels extending transversely therethrough on opposite 55 sides of said wire receiving hole in a direction at an angle thereto, a supporting pin having a head with undercut grooves therein extending into the base of said body and intersecting one of said channels, fastening means extending through said last named channel and engaging said supporting pin to secure said pin in place, and means extending through the other of said channels for locking said fastening means to said body, said fastening 60 means comprising a member having an open-

ing therein through which the head of said pin passes when said member is partially extended through said channel, and a narrow slot leading from said opening adapted to receive the undercut grooves on the head of said pin when said member is completely extended through said channel to prevent rotation of said supporting pin. 70

2. In an insulator, the combination of an insulator body having a plurality of transverse openings therethrough, one of which is disposed between and at right angles to the remaining channels for receiving an associated wire and a recess in the bottom thereof intersecting the lower of said channels, a 80 supporting pin for said insulator projecting into said recess and provided with a head portion having undercut grooves forming a square portion on said pin, a strap extending through said intersected channel having a slot provided with a wide portion through which the head of said pin is passed and a narrow portion for receiving and cooperating with the square portion formed by said undercut grooves for positively locking said pin 85 to said strap member, and means extending through the other of said channels for locking said strap to said body portion. 90

3. The combination in an insulator of a body portion having a recess in the bottom thereof and a transverse channel extending therethrough intersecting said recess, a supporting member having an undercut head portion disposed in said recess, and a fastening means extending through said transverse 10 channel having a slot provided with an enlarged portion at one end through which the head of said supporting member extends and a reduced portion at the other end for engaging the undercut portion of said supporting 10 member and securing the same to said body portion. 95

4. The combination in an insulator of a body portion having a recess in the bottom thereof and a transverse channel extending therethrough intersecting said recess, a supporting member having the head thereof disposed in said recess and a fastening member in the channel having a slot provided with an enlarged portion on one end through 11 which the head of said supporting member extends and a reduced portion at the other end smaller than the head portion of said supporting member for engaging the same below the head and securing said member 11 in place. 120

In testimony whereof, I have hereunto subscribed my name this 2nd day of April, 1929.

CHARLES E. MILLER.
